Primary Examiner — George D. Kirschbaum

(57) **CLAIM**

The ornamental design for a sensor device, as shown and described.

DESCRIPTION

1. Sensor device
- 1.1 : Perspective
- 1.2 : Perspective
- 1.3 : Front
- 1.4 : Back
- 1.5 : Top
- 1.6 : Bottom
- 1.7 : Left
- 1.8 : Right
- 1.9 : Environmental view

Fig. 1.9 represents a perspective view of the sensor device in environmental use; the broken lines depict environment and form no part of the claimed design.
